UNITED STATES PATENT OFFICE.

FRANK N. WILSON, OF ST. LOUIS, MISSOURI.

TEARING DOWN AND GATHERING ARM FOR COAL LOADERS.

Application filed July 7, 1922. Serial No. 573,428.

To all whom it may concern:

Be it known that I, FRANK N. WILSON, a citizen of the United States, residing in the city of St. Louis and State of Missouri, have 5 invented a new and useful Improvement in Tearing Down and Gathering Arms for Coal Loaders, of which the following is a specification.

My present invention relates to tearing 10 down and gathering arm for loaders, such as described in my application for Letters Patent bearing Serial Number, 530,183 now Patent 1,467,700, Sept. 11, 1923 and is a distinct and practical improvement to overcome certain 15 practical objections to, and defects in, the gathering arms disclosed in said application.

The object of my present invention is to provide a tearing down and gathering arm 20 which will have in addition to the orbital movement of the forward end of the arm, a turning movement to gradually raise the forward end of the tearing down and gathering arm after it has gathered and moved lump 25 coal into a pile in advance of and into the path of travel of conveyor arms of a chain conveyor for moving the coal from the pile.

A further object of the invention is to provide the rear end of the tearing down and 30 gathering arm which is preferably square in cross-section, with a quarter turn or twist for reception in a like socket or bearing to impart the turning movement to the arm, as it is reciprocated longitudinally.

With the above and other objects in view, 35 as will appear hereinafter, the invention consists in the novel features of construction, arrangement and combination of parts herein-after more fully described and finally pointed 40 out in the claims hereto appended.

Referring to the accompanying drawings forming a part of this specification, wherein like characters of reference denote similar parts throughout the several views:

Fig. 1, is a side elevation of a conveyor, track to which is applied a tearing down and gathering arm embodying my invention. The arm is shown in side elevation in its extreme extended position.

Fig. 2, is a view similar to Fig. 1, showing the arm in its rearmost position.

Fig. 3, is a plan view of the arm applied to the conveyor track showing the arm in full lines in one position and in dotted lines 55 in three other positions.

Fig. 4, is a plan view of two opposed arms as they appear in connection with coal conveyor means with which the arms co-act.

Fig. 5, is an end elevation of one arm as it appears in dotted lines designated A in Fig. 3.

Fig. 6, is an end elevation of the arm as it appears in full lines designated in Fig. 3.

Fig. 7, is an end elevation of the arm as it appears in dotted lines designated B in Fig. 3.

Fig. 8, is an end elevation of the arm as it appears in dotted lines designated C in Fig. 3.

Fig. 9, is a fragmentary perspective view 70 of the gathering arm and its cooperating bearing.

Fig. 10, is a fragmentary perspective view 75 of a modified form of the gathering arm and the bearing.

Referring to the drawings, the reference character 1 indicates a conveyor table plate mounted upon the rails 2 to constitute an inclined track over which coal may be conveyed or elevated for dumping into suitable 80 vehicles positioned to the rear of the device (not shown).

3 represents suitable chain sprockets which are fixed to the supporting shafts 4 and over which ride endless chains 5 provided with 85 suitable coal conveying arms 6 for dragging the coal up the inclined table 1, as is manifest. Situated above and suitably spaced from the table plate 1 is a plate 7 which covers the conveyor chains 5, as shown in 90 Figs. 1 to 4, inclusive.

In carrying out the aim of my present invention, I suitably fix a suitable crank 8 to the upper face of sprocket 3, so as to rotate therewith.

A suitable bearing 9 is pivotally supported, as at 10 upon the upper face of the crank plate 8 and a suitable distance to the rear of said bearing 9, a second bearing designated 11, is pivotally supported, as at 12, 100 upon the upper face of the chain cover plate 7.

13 indicates a tearing down and gathering arm, preferably square in cross-section, although not necessarily so, which is provided 105 near its forward end with a tubular wrist 14 journaled in the crank plate bearing 9, so as to permit of turning movement of the arm 13.

The rear end of the arm 13 is square in cross-section and twisted or turned a quarter-

turn or the like designated 14' and this end is receivable in a square opening 15 of the rear bearing 11, as more clearly shown in Fig. 9 of the drawing for imparting a turning or partial rotary movement to the arm 13 as it reciprocates or moves longitudinally through the bearing 11.

In Fig. 10 is shown a modified arrangement for imparting to the gathering arm 10 partial rotation movement. The general construction of the gathering arm is the same as before described but the rear end 13^a of the arm 13, instead of being square in cross section and twisted as shown, is of circular cross section and is provided with a longitudinal cam groove 14^a. Also, the rear bearing 11^a has a circular opening 15^a which receives the rear end 13^a of the gathering arm. The bearing 11^a is provided with 20 a lug 16^a which cooperates with the cam groove 14^a to produce the desired partial rotative movement of the gathering arm 13.

The forward end of the tearing down and gathering arm 13 is bent outwardly a short 25 distance as at 16, then extended forwardly and parallel but in advance of the arm 13 proper, as at 17, and then the forward end 17 of the arm is curved inwardly, as at 18 to 30 form a pick point, or finger. The forward end of the arm 13 is substantially shallow U-shaped so as to grasp and move to a central point a quantity of lump coal to be carried away by moving conveyor arms to 35 a suitable discharge point where the coal will be received by a suitable vehicle or dumped into a pile from an elevated position.

The movement of travel of the tearing down and gathering arms is an essential 40 feature of this invention, which, of course is due entirely to the structure of the arm and its associated parts, as is apparent from the drawings. The function of the arms 13 is to first tear down the coal, if necessary, in 45 its forward movement in a fixed orbital path, then gathering and moving the coal from two sides to a central location in a pile to be removed by the arms of endless conveyor chains working in unison. The forward curved ends of the arms 13, it is 50 manifest from Fig. 3, first move continuously in an arcuate path from the position shown in full lines in Fig. 3 to the position shown in dotted lines designated A, then to the 55 position shown in dotted lines B, then position shown in dotted lines designated C and finally back to the position shown in full lines which completes the movement 60 of the forward end of the arms in their orbital path, which movement is due to the arm being connected to the crank plate near its forward end and guided at its rear end by the bearing 11.

The position of the forward end of the 65 arm 13 is upright when in its rearmost posi-

tion, as shown in full lines in Fig. 3 and in Fig. 6. When in the position shown in dotted lines A in Fig. 1, the arm 13 is slightly turned at an angle as more clearly shown in Fig. 5. When in the position shown in dotted lines B in Fig. 3, the arm 13 is flat or in a horizontal position as more clearly shown in Fig. 7, and, when in the position as shown in dotted lines C in Fig. 3, the arm is turned again to an angle, as more clearly shown in Fig. 8. The turning movements of each arm in the preferred form of the invention, is imparted through the twisted rear end of the arm reciprocating longitudinally in the square opening of the rear bearing 11, and in the modified form of the invention through the cam action between the lug 16^a and the cooperating groove 14^a in the rear end 13^a of the gathering arm. 70 75 80 85

From the dotted lines D shown in Fig. 3, it is evident that the forward end of the arm travels in an elliptical orbital path and during the greater part of its travel, say three fourths thereof, the arm is also partially rotating in its supporting bearing, due to the 90 twisted rear end of the arm longitudinally reciprocating within bearing 11.

While I have shown and described the preferred forms embodying my invention including two arrangements for producing partial rotation movement of the gathering arm, it will be apparent to those skilled in the art that changes in the construction may be made without departing from the invention within the scope of the appended claims. 95 100

Having thus described the invention, what is claimed is:

1. In a loading machine, a gathering arm, means to impart to said arm an orbital movement and means to simultaneously impart to said arm a partial rotative movement. 105

2. In a loading machine, an endless conveyor, gathering arms cooperating with the endless conveyor, means for moving each 110 of said gathering arms in a fixed orbital path, and means for partially rotating said gathering arms by and upon said first-named movement thereof.

3. In a loading machine, an endless conveyor provided with conveying arms, gathering arms cooperating with the conveying arms, means for moving said gathering arms in fixed orbital paths, and automatic means for partially rotating said 120 gathering arms by and upon said first-named movement thereof.

4. In a machine of the class described, an endless conveyor provided with rotating disks, crank arms pivoted eccentrically in 125 said disks, gathering arms journaled in the crank arms and means to effect turning movement of the gathering arms.

5. In a machine of the class described, an endless conveyor provided with rotating 130

disks, crank arms pivoted eccentrically in said disks, pivoted guide members, tearing down and gathering arms having their forward ends journaled in said crank arms, and their rear ends movable in said pivoted guide members and means to effect turning movement of the tearing down and gathering arms.

6. In a coal loading machine, a pair of opposed gathering arms, means to move said arms toward each other so as to gather the coal between the arms and to move same into a pile, and means to automatically raise the arms up from the coal pile subsequent to the said gathering movement thereof.

7. In a coal loading machine, a gathering arm, means to pivotally mount said arm, means to oscillate the arm about the pivotal means, and means for automatically turning the arm by and upon oscillation thereof.

8. In a coal loading machine, a gathering arm having a cylindrical wrist and a twisted portion, a pivoted bearing receiving the twisted portion and formed to rotate the arm upon longitudinal movement of the latter through the bearing, a crank, and a second bearing pivoted to the crank and rotatably receiving said wrist whereby to oscillate the arm and to longitudinally move same through the first bearing to cause the

latter to effect simultaneous rotary movement of the arm.

9. In a coal loading machine, a gathering arm, means to rotatably mount said arm adjacent its forward end, means to slidably and rotatably mount the rear end of the arm, means to oscillate said first named mounting means and thereby effect longitudinal sliding of the rod, and means to effect rotation of the arm by and upon sliding thereof.

10. In a coal loading machine, a gathering arm, means to oscillate and simultaneously effect longitudinal movement of the arm, and means operable by and upon longitudinal movement of the arm to automatically impart turning movement to the arm.

11. In a coal loading machine, a gathering arm, means adjacent to the outer end of the arm to oscillate and simultaneously effect longitudinal movement of the arm, means for mounting the inner end of the arm to permit of longitudinal movement thereof, and means whereby to automatically impart turning movement to the arm upon said longitudinal movement thereof.

In testimony whereof, I have hereunto signed my name to the specification.

FRANK N. WILSON.
